UNITED STATES PATENT OFFICE.

JOHN C. HARJU, OF MICHIGAN, NORTH DAKOTA.

COMBINATION-PLIERS.

1,185,398.

Specification of Letters Patent. Patented May 30, 1916.

Application filed February 21, 1916. Serial No. 79,730.

To all whom it may concern:

Be it known that I, JOHN C. HARJU, a citizen of the United States, residing at Michigan, in the county of Nelson, State of North Dakota, have invented certain new and useful Improvements in Combination-Pliers; and I do hereby declare the following to be a full, clear, and exact description of the invention, such as will enable others skilled in the art to which it appertains to make and use the same.

The present invention is directed to improvements in combination pliers, and has for its object to provide a tool of this nature having combined therewith devices for cutting and punching machine belts.

A further object of the invention is to provide a tool of this nature constructed in such a manner that the attachments for punching and cutting belts will in no way interfere with the operation of the tool as a plier.

A still further object of the invention is to provide novel means for adjustably connecting the belt hole punches to the handles of the plier.

With these and other objects in view, this invention resides in the novel features of construction, formation, combination and arrangement of parts to be hereinafter more fully described, claimed and illustrated in the accompanying drawing, in which:

Figure 1 is a plan view of the plier, showing the belt cutting attachment in its operative position. Fig. 2 is a fragmentary plan view of the plier, showing the belt cutting attachment about to be engaged or disengaged from the jaws of the plier. Fig. 3 is a sectional view on line 3—3 of Fig. 1. Fig. 4 is a sectional view on line 4—4 of Fig. 1. Fig. 5 is a detail sectional view, showing the cutting attachment in its inoperative position. Fig. 6 is a fragmentary side elevation of one of the handles. Fig. 7 is a detail sectional view through one of the handles. Fig. 8 is a similar view through the other handle.

Referring to the drawing 1 indicates the jaws which are pivotally connected, as at 2 in crosswise relation, as is usual, said jaws terminating in tubular handles 3, each of said handles being provided with a plurality of perforations 4, the purpose of which will appear later.

Slidably mounted in one of the handles 3 is a punch 5, said punch having engaged

transversely therein a pin 6, said pin being attached to one end of a leaf spring 7, the other end of which is fixed in the punch, as at 8. The pin slides in the slot 9 formed in the handle, and limits the sliding movement of the punch in opposite directions.

The pin 8 is adapted to engage in selected perforations 4 so as to hold the punch in adjusted positions, whereby the punching operation can be limited. The spring 7 normally holds the pin in one of the perforations so as to prevent movement of the punch. Similarly mounted in the other handle is a punch hole opener 10, the same being mounted and operable in the same manner as the punch 5.

Connected to one of the jaws 1 is a plate 11, said plate having hingedly connected thereto an arm 12, the free end of which having fixed thereto a blade 13. Carried by the arm 12 is a transverse arm 14, which has adjustably mounted thereon a gage 15, said gage being adjustable so as to regulate the action of the blade 13. The gage 15 is adapted to slidably engage one edge of the belt as the blade is drawn therealong so as to trim the belt. To hold the arm 12 in its operative position a rod 16 is provided and is engaged in the arm and fixed transversely thereof.

The jaws 1 are each provided with recesses 17 which are adapted to receive the ends of the rod 16 when the jaws are nearly closed, thus firmly holding the arm, when the cutting blade 13 is being used, since a slight pressure exerted on the handles 3 will firmly hold the ends of the rod in said recesses.

One of the jaws is provided with a socket 18, which is of a depth sufficient to receive the cutting blade 13 when the arm 12 is in its inoperative position, and as clearly shown in Fig. 5 of the drawing.

From the foregoing description it will be seen that a tool has been provided having combined therewith a variety of useful attachments.

What is claimed is:

1. A device of the class described comprising pivotally connected jaws, handles for the jaws, an arm hingedly connected to one of the jaws, a cutting blade carried by the arm, a rod extending through the arm, and means carried by the jaws for engaging the ends of the rod to hold the same in its operative position.

2. A device of the class described comprising pivotally connected jaws, a plate fixed to one of the jaws, an arm hingedly connected to the plate, a cutting blade carried by the arm, a rod fixed transversely of the arm, said jaws having recesses formed therein for detachably receiving the ends of the rod to hold the arm in its operative position, said arm being capable of being folded

upon the jaw to which it is hinged when in its inoperative position.

In testimony whereof, I affix my signature, in the presence of two witnesses.

JOHN C. HARJU.

Witnesses:

GEORGE D. KELLEY,
IRA EDWARDS.
